UNITED STATES PATENT OFFICE.

JAMES C. ANDERSON, OF HIGHLAND PARK, ILLINOIS.

METHOD OF MAKING CLAY BUILDING-BLOCKS IN IMITATION OF STONE.

SPECIFICATION forming part of Letters Patent No. 424,251, dated March 25, 1890.

Application filed December 4, 1888. Renewed March 1, 1890. Serial No. 342,206. (No model.)

To all whom it may concern:

Be it known that I, JAMES C. ANDERSON, a citizen of the United States, residing at Highland Park, in the county of Lake and State 5 of Illinois, have invented new and useful Improvements in Methods of Manufacturing Clay Building-Blocks in Imitation of Stone; and I do hereby declare the following to be a full, clear, and exact description of said invention, reference being had to the accompanying drawings, and to the letters of reference marked thereon, which form a part of this specification.

My invention relates to a new and useful 15 method of manufacturing bricks or blocks from clay.

The object of my invention is to produce 20 bricks or blocks from clay in imitation of the various stones, having a roughened or granulated surface representing the natural cleavages of the stone, as well as the natural colors.

My invention consists, therefore, of forming 25 a block or brick of a sufficient size for making two or more blocks or bricks of a series of thin slabs of clay pressed or compacted together to form a solid body, and in then pulling or severing the block into two or more sections between the layers, so as to produce a fractured or roughened surface on the brick 30 or block.

In the drawings, Figure 1 is a longitudinal 35 sectional view of the mold-box in which the blocks or clay bodies are formed and a side view of the mold, charger, and plunger. Fig. 2 is a side view of the mold-box, showing the movable section in its forward or closed position. Fig. 3 is also a side view of the mold-box, showing the movable section in an open position.

40 In an application filed by me April 19, 1888, Serial No. 271,193, I have shown, described, and claimed a machine for making large bodies or blocks of clay, said bodies or blocks being made up of thin slabs or layers of clay, the same being caused to adhere together by 45 means of a slip or wetted surface.

In the machine above referred to the die or mold-box is open at one end, and as each layer of clay is pressed onto the previously 50 pressed and compacted body the said body is

forced through the mold-box and has its exit at or through the open end of the mold-box.

In carrying out my invention I use essentially the same machine with the shafts, wheels, cams, levers, &c., for operating the 55 plungers, clay-charger, and other portions of the machine, and only such parts are shown here as serve to carry out my method.

A indicates the mold-box, in which the articles are compressed by the plunger B, said 60 mold-box being divided into two sections C and D, the section C being rigid or firmly secured to the frame of the machine, while the section D is capable of a slight longitudinal movement and is guided in said movement by suitable guides or ways E, so as to prevent said section from moving in a transverse direction. The plunger B works through the charger F to press the clay therefrom onto the previously - formed clay body. Said 70 charger, when it returns to its upper position to receive its charge from the clay-box, (not shown,) carries with it the slip-rolls H and I, which moisten or deposit a layer of slip onto the clay slab last pressed, the rolls H and I 75 receiving the slip or moisture from the tank K.

I will now proceed to describe the devices by which the clay bodies are torn into blocks of the desired size, so as to form the roughened or fractured surface.

The section D of the mold-box is connected to the section C by means of links L and bell-crank levers M, one on each side, the point of union between the links L and levers M forming a toggle-joint. The bell-crank levers M are pivoted to the side of the sections C of the mold-box, as shown at N, while the long arm O of said lever projects upward and is provided with a stud a, which extends out to one side and enters the groove b in the 90 ratchet-wheel P. The ratchet - wheel P is mounted in suitable bearings and provided with ratchet-teeth adapted to receive the pawl R, said pawl being pivoted to the rocking levers S. The lower end of the lever S is pivoted to the axis of the ratchet-wheel or to any other suitable point, while its upper end is secured to the end of the pitman T, the other end of the pitman being secured to the yoke U, to which the plunger B is attached and by 100

which the plunger is operated. The groove *b* in the ratchet-wheel *P* is concentric with the axis of said wheel, except at the point *c*, where an offset is formed on the outer wall 5 of said groove, which, coming in contact with the stud *a* on the bell-crank lever, causes the same to rock back and forth, moving the section *D* toward and from the section *C* to tear or sever the clay body at that point. A slab 10 of clay is pressed upon the previously-formed slab at each forward movement of the plunger and caused to adhere to the same by means of the layer or coating of slip or moisture deposited by the rolls *H* and *I*, so that 15 the block produced is practically a solid one. The connections between the ratchet-wheel and yoke *U* are such that at each backward movement of the plunger the ratchet-wheel is moved one tooth. The pin *a* on the lever *M*, 20 traveling in the plain or circular portions of the groove *b*, allows or admits the clay slabs to be formed or compacted together; but when the stud *a* reaches the point *C* in the slot the upper end of the bell-crank lever is 25 thrown forward, as shown in Fig. 3, and causes the links *L* and the portion of the bell-crank connected to it to assume a horizontal line. This forces the section *D* away from the section *C* and tears the clay body apart 30 on the line with the end of the section *C*, thus causing a fracture between the portions severed representing the natural cleavage of stone.

After the stud *a* has passed the point or 35 short curve *c* in the groove *b* the upper end of the lever is thrown back, bringing the section *D* in contact with the section *C* and

pressing the fractured faces of the clay bodies together again, so as to press the granules of clay which have become loosened by the fracture into the faces of the blocks, and giving to the same a firm texture or skin and at the same time preserving the full granular roughened surface; and when the burning has taken place the granules become so firmly 45 fixed that no possible disintegration can take place by thermal changes or osmotic action.

The ordinary clay for making red brick may be used; but I prefer to use a pure clay mixed with metallic oxides, which will give 50 the desired color to imitate brownstone, grey-stone, granite, or any of the plain-colored stones, and by the use of clays of different color I produce an imitation of onyx, jasper, and, in fact, of all kinds of variegated stones. 55

In applications filed of even date herewith, Serial Nos. 292,582 and 292,584, I have claimed the machine and the article, and such I do not claim in this application.

What I claim is—

An improvement in the art of making building-blocks in imitation of stone, which consists in making a body or block of a series of thin slabs of clay of the desired color, and in then tearing such body in two to form 65 faces representing the natural fracture of stone.

In testimony whereof I affix my signature in the presence of two subscribing witnesses.

J. C. ANDERSON.
